Franklin V. Slough
ATTORNEY.

UNITED STATES PATENT OFFICE.

ELSIE A. MARTIN, NÉE BLACKSTUN, OF ST. LOUIS, MISSOURI.

COMBINATION POCKET IMPLEMENT.

Application filed February 17, 1921. Serial No. 445,834.

To all whom it may concern:

Be it known that I, ELSIE A. MARTIN, née BLACKSTUN, a citizen of the United States, residing at St. Louis, in the city of St. Louis, and State of Missouri, have invented certain new and useful Improvements in Combination Pocket Implements, of which the following is a specification, reference being had therein to the accompanying drawings.

10 This invention relates to implements embodying a plurality of units, each unit embodying a plurality of utilities and foldable into compact space, and a container protecting the implements from damage either to 15 such implements or which might be inflicted by the implements externally.

A further object of the invention is to provide a device which shall embody not only a casing for a plurality of implements 20 but a handle and marker for a key-ring, a device whereby the keys are more conveniently handled and may carry the owner's name to identify them if lost.

With these and other objects in view the 25 device comprises certain novel elements, combinations, and arrangements of parts as will be hereinafter more fully described and claimed.

In the drawings:

30 Figure 1 is a view in side elevation of the device with the implements partly swung out of the case into view;

Fig. 2 is a perspective view of the device with the implements in closed compact position;

Fig. 3 is a transverse sectional view of the device as indicated on line 3-3 of Fig. 2; and

Fig. 4 is a transverse sectional view on line 40 4-4 of Fig. 2.

Like characters of reference indicate corresponding parts throughout the several views.

The improved pocket implement which 45 forms the subject matter of this application comprises a casing or handle member 10 of channel formation, which may be of any approved construction and material, preferably of stamped metal, although it is to be 50 understood that the present invention is in

no way limited to such material. At one end the casing is provided with an eyelet 11 through which is inserted a key-ring 12 carrying keys in the usual and ordinary manner said eyelet being upset at its opposite 55 ends upon the opposite exterior surfaces of the channel handle. The eyelet also serves as a pivot pintle for a plurality of pivotally combined instruments as for instance a nail-file 13 terminating in a button-hook 14, a 60 comb 15 having the back at 16 more or less sharpened, which in conjunction with the extremity 17 serves as a paper cutter and envelop opener. Also preferably upon the back of the handle or the side opposite the 65 opening to receive the members 13 and 16 a pencil-holder 18 is mounted composed of any approved material and of any approved form for holding the pencil 19 therein.

The handle may also be employed for the 70 purpose of applying a name thereto, as indicated at 20, serving not only, therefore, as a handle for the keys and a container for the implement, but as an identification tag to make possible the return of the implement if 75 lost. At the end opposite the eyelet the handle is provided with abutting flange sections 21, which form a partial closure for that end of the handle, so that the several instruments, as 13 and 16, fold entirely with- 80 in the channel.

It is believed that from the foregoing description in conjunction with the drawings the use and utility as well as the operation of the device will be fully and clearly understood.

What I claim to be new is:

A combination pocket implement comprising a handle composed of an integral sheet of material folded to channel formation with 90 abutting flanges forming a partial closure at one end, an eyelet inserted through the end opposite the abutting flanges and upset upon opposite exterior surfaces of the channel, and a plurality of instruments pivoted upon 95 the eyelet and foldable entirely within the channel.

In testimony whereof I hereunto affix my signature

ELSIE A. MARTIN, NÉE BLACKSTUN.
